UNITED STATES PATENT OFFICE.

CHARLES H. LOW, OF SANDWICH, ILLINOIS, ASSIGNOR OF ONE-HALF TO
J. PHELPS ADAMS, OF SAME PLACE.

DRIVE-CHAIN.

SPECIFICATION forming part of Letters Patent No. 252,609, dated January 24, 1882.

Application filed August 29, 1881. (No model.)

To all whom it may concern:

Be it known that I, CHARLES H. Low, a citizen of the United States, residing at Sandwich, in the county of De Kalb, in the State of Illinois, have invented certain new and useful Improvements in Drive-Chains, which are fully set forth in the following specification, reference being had to the accompanying drawings, in which—

10 Figure 1 represents a plan view of two of my improved drive-chain links coupled together; Fig. 2, a longitudinal section of the same, taken on the line $x'x$, Fig. 1; Fig. 3, a cross-section of the same at the coupling, taken on the line 15 $y'y$ in Fig. 1; and Fig. 4, an elevation showing the application of a drive-chain embodying my improvement.

My invention relates to drive-chains composed in whole or part of detached links, and 20 particularly to the chain known as the "Ewart chain," upon which it is an improvement. In the Ewart chain the end bars, which couple with the hooks, are straight and of uniform size as well as the hooks, and this construction 25 produces a certain stiffness in the chain, which prevents it from being used by crossing, so as to secure reverse motion, and therefore limits the application of this drive-chain to this extent. My present improvement is intended to 30 obviate this difficulty and to adapt the chain for use crossed, so as to secure reverse motion in the well-known way.

The invention consists in providing the links with coupling-bars of oval form longitudinally, 35 and also in the combination of links with such end bars with links also having coupling-hooks with enlarged or flaring openings at their ends, whereby a lateral rocking movement is permitted at the coupling.

40 I will proceed to describe one way in which I have carried out my invention practically, and the improvement which I desire to secure by Letters Patent will then be pointed out definitely in the claims.

45 In the drawings the links are shown of general form, like the well-known Ewart link. The side bars, A, and the hook end bar, B, are the same as in the Ewart link, and do not require special description. One or both of the 50 side bars are provided with notches or depres-

sions a , the same as in the Ewart link, by means of which the links are readily coupled and uncoupled. The coupling end bar, C, of the links, however, instead of being straight and of uniform size, is enlarged slightly centrally and diminished in size slightly toward its respective ends, so as to give it an oval form in the direction of its length, as shown clearly in Figs. 1 and 3 of the drawings. The links 55 are provided with coupling-hooks D on the opposite end bars, which, in the main, are like the Ewart coupling-hooks; but the seat portion of the hook—that is, that portion which makes the principal bearing for the coupling end bar—is cut away somewhat at each end of 60 the hook, as shown at d in Fig. 3 of the drawings, thereby gradually enlarging the open space within the hook from the center outward toward each end. Preferably this cutting away of the hook is on the arc of a circle, so as to 65 make a curved seat, as shown in Fig. 3 of the drawings.

The coupling end bars are inserted in the hooks to couple the links together in the same way as in the Ewart chain. Obviously when 70 the links are coupled together the construction above described permits a rocking motion laterally, so that the links may be twisted with reference to each other to quite an appreciable extent. This capability of a twisting movement of the links enables the chain to be crossed, 75 as shown in Fig. 4 of the drawings, so as to secure reverse motion in the well-known way with cross-bands, and in this arrangement the chain will work with the usual flexibility and 80 without binding, and thus the application of this class of drive chains for practical purposes 85 is considerably enlarged.

The cutting away of the hook is not absolutely necessary, for if the hook-opening be 90 reasonably large a certain amount of movement in the direction mentioned will be permitted without enlarging the openings at the ends. The best and most satisfactory results will be obtained, however, by modifying the 95 form of both hook and end bar, as shown and described. I do not wish to be understood, however, as limiting my invention to the changed form of both. Neither do I limit myself to an end bar of circular form in cross-section, as 100

shown in the drawings, for the cross-section may be oval also, or some other form, and my improvement may also be applied to a different kind of coupling device from that shown 5 and described in the drawings, so that I do not wish to be understood as limiting the application of my improvement to such links as are used in the Ewart chain. It is also obvious that the end bar is not necessarily a true 10 oval lengthwise. This form may be changed, provided always there is an appreciable enlargement of the central portion of the bar.

I do not here claim the hooks with flaring end 15 openings as a separate device, or when used with coupling-bars of substantial uniform size, for this matter will be made the subject of a separate application.

Having thus described my invention, what I claim as new, and desire to secure by Letters Patent, is—

20

1. In a drive-chain; a rectangular link provided with a coupling end bar of oval form lengthwise, substantially as and for the purpose set forth.

2. In a drive-chain, a coupling end bar on 25 one link of oval form lengthwise, in combination with a coupling-hook on the adjacent link cut away to provide flaring openings at the ends of the hooks, substantially as and for the purposes set forth.

CHARLES H. LOW.
